FIRE ALARMS**Robert K. Youtie, Haddonfield, N. J.****Application February 27, 1956, Serial No. 567,938****3 Claims. (Cl. 116—106)**

This invention relates generally to heat responsive signals, such as fire alarms, of the type adapted to be operated by pressurized fluid actuating sound producing means.

A particular embodiment of the present invention, which is illustrated in the drawings and which will be described hereinafter in greater detail, comprises generally a vessel for containing pressurized fluid, fluid actuatable sound producing means connected to the vessel for actuation by fluid from the vessel, and closure means normally preventing actuation of the sound producing means by the pressurized fluid and responsive to excessive temperature to permit such actuation of the sound producing means.

While there are many such fire alarms in the prior art and on the market, all of these devices are constructed with the closure means ahead of the sound producing means, i. e., between the sound producing means and the pressurized fluid supply. In this arrangement complete removal of the closure means requires passage of the latter through and out of the sound producing means; or, some provision must be made to receive the closure means out of the path of actuating fluid so as not to obstruct the fluid flow. The through passage or complete expulsion of the closure means is not always feasible or reliable in practice, so that the closure means often remains in the system after having been released from its closing relation in response to excessive temperature, and serves to obstruct, reduce, or entirely prevent the desired flow of fluid necessary to actuate the sound producing means. Removal of the closure means other than by passage through the sound producing means usually requires a relatively complex construction and involves increased costs.

Accordingly, it is a general object of the present invention to provide a heat responsive signal or fire alarm of the type described which overcomes the above mentioned difficulties, which is simple and durable in construction, and reliable in use, and which can be economically manufactured and sold at a reasonable cost.

It is a more particular object of the present invention to produce a fire alarm having the advantageous characteristics mentioned in the foregoing paragraph, and wherein the closure means is located down stream of or at the fluid outlet of the sound producing means, so that upon thermal responsive release of the closure means it is positively removed out of and away from the sound producing means.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

2

In the drawings:

Figure 1 is a top perspective view showing a thermal responsive signal or fire alarm constructed in accordance with the present invention;

5 Figure 2 is an elevational view, partly in section, taken substantially along the line 2—2 of Figure 1;

Figure 3 is a horizontal sectional view taken substantially along the line 3—3 of Figure 2;

10 Figure 4 is a partial, sectional elevational view showing a slightly modified construction of the present invention; and

Figure 5 is a horizontal sectional view taken substantially along the line 5—5 of Figure 4.

Referring now more particularly to the drawings, and 15 specifically to Figures 1—3 thereof, the embodiment of the invention illustrated therein comprises a vessel or container, generally designated 10, and a sound producing device or whistle 11 connected to the vessel.

The vessel 10 may be of generally cylindrical configuration, including a lower end closure or bottom wall 13, an upstanding generally cylindrical side wall 14 having its lower end extending peripherally about and secured to the bottom wall, and having its upper portion turned inwards, as at 15, to define an upper end or top wall for the container. The container top wall 15 is provided with a central, annular, upstanding lip or flange 16 which circumscribes a through opening formed in the container top wall. In practice, it has been found satisfactory to employ containers of the pressure-resistant type commonly used in aerosol devices.

The sound producing device or whistle 11 is mounted within the top wall flange 16, serving to close the top wall opening, and includes a generally cylindrical cup shaped member or inner cap 19, and an outer cup shaped member or cap 20 received partially within the inner cap. The inner cup shaped member 19 is formed with a flat, generally horizontally disposed bottom wall 21, and a generally cylindrical upstanding side wall 22 extending about the periphery of the bottom wall and having its 40 upper peripheral edge portion 23 bent or curled outwards and downwards to define a lip, engaging over the annular top wall lip 16. A suitable sealing compound (not shown) is interposed between the top wall flange 16 and out turned edge portion or lip 23 of the inner cap; and, the 45 cylindrical side wall 22 is crimped or deformed outwards, as at 24, interiorly of the container 10 just below the container top wall 15, so as to retain the cup member lip 23 in tight sealing engagement with the top wall lip 16. In addition, the cup member side wall 22 is formed with 50 a through aperture or port 27 spaced between the cup member bottom wall 21 and crimped or deformed side wall portion 24. Interiorly of the cup member 19 is provided a conduit 28 which extends along the cup member side wall 22 communicating at one end through the port 27 with the upper interior region or head space of the vessel 10, and opening at its other end 29 interiorly of and substantially tangential to the cylindrical inner cup side wall 22. Thus, the conduit 28 communicates from the inclosed space defined by the vessel 10 and inner cup member 19, to the interior of the inner cup member, opening substantially tangentially into the latter.

The outer cup member or cap 20 includes a generally flat, horizontally disposed bottom wall 32 located within the cup member 19 parallel to and spaced upon the bottom wall 21 of the latter cup member, and an upstanding peripheral side wall 33 crimped or deformed outwards into the deformation 24 of the inner cup member side wall 22 and having its upper peripheral edge portion or lip 34 turned or bent outwards over the edge portion 23 and lip 16. A suitable sealing compound (not shown) is preferably interposed between the bent edge portions 23

and 34 to provide a fluid tight seal therebetween. Centrally of the outer cup member bottom wall 32, and substantially perpendicular thereto, is provided an upstanding or outwardly projecting cylindrical tube or conduit 35 having its lower end opening through the outer cup member bottom wall and into the generally cylindrical space 30 between the inner and outer cup member bottom walls.

Secured in closing relation within the upper or outer end portion of the conduit or tube 35 is a closure member or plug 36. The closure member of plug 36 may be formed of any desired material and secured in closing relation within the conduit 35 by heat fusible material, such as solder or the like, at 37. If desired, the plug may also be fabricated of solder or other fusible material.

Before assembling the inner and outer cup members 19 and 20 of the sound producing device or whistle 11 with the vessel 10, the vessel is filled with a suitable fluid 40 under pressure, such as carbon dioxide, nitrous oxide or a fluorinated hydrocarbon, the latter being readily capable of partial liquification. The inner and outer cup members 19 and 20 are then secured in place and combine to define with the vessel 10 a pressure resistant sealed enclosure.

With the device of Figures 1 and 2 in its pressurized but inactive or quiescent state, the inner cup side wall port 27 opens into the head space of the vessel 10 so that the gaseous phase of the partially liquified contents 40 are communicable through the conduit 28 with the interior of the cylindrical chamber 30 defined between the inner cup member side and bottom walls 21 and 22 and the outer cup member bottom wall 20, and are further communicable with the interior of the conduit 35 to exert pressure upon the closure member or plug 36. When the ambient atmosphere attains a predetermined temperature sufficient to fuse the plug securing material 37, the fluid pressure interiorly of the sound producing means 11 will expel the plug out of and away from the conduit 35. Thus, the gaseous phase of the propellant 40 is free to pass at substantial velocity from the vessel 10 through the conduit 28, entering the interior of the cylindrical whistle chamber 30 tangentially thereof, from which it flows outward through the conduit 35 to the ambient atmosphere. The conduit 28 thus defines an inlet for directing the propellant gas tangentially into the cylindrical chamber 30 so that the gas forms a vortex therein. Also, the conduit 35, disposed axially of the cylindrical chamber, defines the only outlet for the fluid of the vortex, so that an exiting vortex of substantially reduced radius, and hence of substantially increased velocity is formed in the outlet conduit 35. As this exiting vortex emerges from the open end of the outlet conduit 35 a shrill whistle is produced.

Upon egress of gaseous state propellant from the head space of the vessel 10, liquid phase propellant becomes gaseous and provides a continuous fluid flow through the whistle for a substantial period of time.

A slightly modified form of the present invention is shown in Figures 4 and 5, wherein 10' designates a vessel corresponding to the vessel 10, having a top wall 15' formed with an upstanding annular lip or flange 16' circumscribing a top wall opening. A cup shaped member or cap 42 is crimped or deformed into sealing engagement within the top wall opening; and, a sound producing device or whistle 11' communicable between the interior and exterior of the vessel 10' is carried in the cap 42.

The whistle 11' includes an upstanding, generally vertically disposed fluid inlet or tubular conduit 43 secured in the cap 42 and having its lower end opening downwards into the gas filled headspace interiorly of the vessel 10'. On the outer end of the conduit 43 and communicating therewith, is formed a resonant chamber 44 having a generally rectangular outlet opening 45. The

upper and lower edges of the outlet opening 45 may be beveled or chamfered inwards, as seen in Figure 4, while the side edges of the opening may be in parallelism, as seen in Figure 5. Secured within and in closing relation with respect to the fluid outlet 45 is a closure member or plug 46. The plug may be fabricated entirely of fusible material or of relatively non-fusible material, in a manner similar to that illustrated and described in connection with Figure 2.

10 The plug 46 thus closes and seals the space defined within the vessel 10' and whistle 11' and retains pressurized fluid in the space. The chamfered upper and lower edges of the fluid outlet 45 aid the plug 46 in resisting the fluid pressure.

15 Upon elevation of ambient temperature to a predetermined degree, the closure member or plug 46 will fuse, or its securing material will fuse, and the closure member will be expelled out of the opening away from the whistle 11' by the fluid contained under pressure. The 20 fluid will then be free to flow without obstruction from the vessel 10' upwards through the inlet conduit 43 and out through the outlet opening 45, whereupon the whistle is actuated to produce a warning sound.

From the foregoing, it is seen that the present invention 25 provides a heat responsive signal or fire alarm which fully accomplishes its intended objects, and which is well adapted to meet practical conditions of manufacture and use.

Although the present invention has been described in 30 some detail by way of illustration and example for purposes of clarity of understanding, it is understood that certain changes and modifications may be made within the spirit of the invention and scope of the appended claims.

35 What is claimed is:

1. A heat responsive alarm comprising a vessel adapted to contain fluid under pressure, fluid actuatable sound producing means having a fluid inlet and a fluid outlet, said sound producing means being connected to said 40 vessel with said fluid inlet communicating with the interior of said vessel for receiving said fluid and said fluid outlet communicating with the exterior of said vessel for passing said fluid through and actuating said sound producing means, and closure means located within said fluid outlet and there secured by heat fusible material in closing relation with respect to said fluid outlet to retain said fluid against the pressure thereof within said vessel and sound producing means, whereby the application of heat sufficient to fuse said fusible material releases said closure means for expulsion of the latter exteriorly of said vessel and sound producing means by the force of said fluid so that the fluid passes through and actuates said sound producing means without obstruction.

50 2. A heat responsive alarm according to claim 1, said sound producing means comprising a generally cylindrical chamber, an inlet conduit defining said fluid inlet and communicating between the interior of said vessel and the interior of said cylindrical chamber, said inlet conduit being arranged to open substantially tangentially into said cylindrical chamber, and a tubular outlet conduit defining said fluid outlet and communicable between the interior of said cylindrical chamber and the ambient atmosphere, said outlet conduit extending from one end 55 of said cylindrical chamber coaxially therewith.

60 3. In an alarm construction, a fluid actuatable sound producing device comprising a generally cylindrical chamber, a fluid inlet conduit adapted for connection to a source of fluid supply and communicating with the interior 65 of said chamber, opening into the latter substantially tangentially thereof to produce vortex flow of fluid in said chamber, and an elongate fluid outlet conduit having an internal surface which is entirely smooth and of circular cross sectional configuration throughout its length, said outlet conduit being of an internal diameter consid-

erably less than that of said chamber, said outlet conduit being arranged coaxially of said chamber having one end fixedly secured to and opening inward through one end of said chamber for receiving a highly accelerated vortex flow of fluid from said chamber, the other end of said outlet conduit providing a discharge outlet for said highly accelerated vortex flow of fluid to produce sound.
